UNITED STATES PATENT OFFICE.

OTTO BLOMBERG, OF CHICAGO, ILLINOIS.

VALVE-SPRING LIFTER.

Application filed September 4, 1926. Serial No. 133,539.

This invention relates to a valve spring lifter.

One object of the invention is to provide a valve spring lifter having relatively adjustable parts to make the lifter universal in so far as size is concerned so that the same tool may be used in connection with engines and valves varying in size.

Another object is to provide a valve spring lifter including a quickly adjustable member releasably locked in position to facilitate application and operation of the lifter.

Another object is to provide a valve spring lifter having a member engageable with a motor part such as the valve guide and which is arranged to prevent injury to such part when it is given a pivotal movement thereon for placing the valve spring in position.

Another object is to provide a valve spring lifter having the various parts cooperate in an improved manner to meet all of the requirements under service conditions.

These and other objects are accomplished by means of the arrangement disclosed on the accompanying sheets of drawings, in which—

Figure 1 is a front elevation of a valve spring lifter embodying my invention;

Figure 2 is a view taken in the plane of line 2—2 of Figure 1 of the same tool;

Figure 3 is a top plan view of said valve spring lifter;

Figure 4 is another front view of the valve spring lifter showing the upper arm or member thereof in a reversed position to enlarge the effective size of the tool;

Figure 5 is an enlarged, sectional, detail view taken in the plane of line 5—5 of Figure 1;

Figure 6 is a front elevation of the valve spring lifter illustrating the compression of a valve spring to release a valve of an internal combustion engine, the latter of which is shown in section; and

Figure 7 is a similar view showing the slide rod of the valve lifter reversed in position with its rounded end in engagement with the valve guide for placing the valve spring in position before the valve is inserted.

The various novel features of the invention will be apparent from the following description and drawings and will be particularly pointed out in the appended claims.

Referring to the figures of the drawings

it will be noted that the valve spring lifter includes a main supporting bar 10 to which a two pieced upper arm or member 11 is secured by bolts 12. The piece 13 of the two pieced member 11 is the one which is directly secured to the support 10, and the other piece 14 of the two pieced member is secured to the member 13 by bolts or screws 15. As shown in Figure 1, the member 11 is secured to the member 10 in one position and in Figure 4 it is secured in a reverse position to enlarge the effective size of the tool.

Slidably mounted in a slot 46 in the enlarged end 16 of the member 14 is a rod 17. One end of the rod 17 is tapered to a point as shown at 18 for engaging the top of a valve 19 for holding the latter down as the valve spring 20 is compressed or raised for releasing the segmental valve spring collar key 21, which normally is seated in a groove in the lower end of the valve stem 22, as shown particularly in Figure 6. The slide rod 17 normally is releasably locked in adjusted position by a bolt 23, having an enlarged slot 24 for receiving the rod 17. The bolt 23 is drawn into a rod locking position by a winged nut 25. In effect, therefore, the locking bolt 23 is a wedge member and has a wedging action upon the slide rod 17 for locking the latter in position. Preferably, a split, circular spring 26, having its free ends opposite, as is usual in that type of spring, is interposed between the winged nut 25 and the head 16 to prevent said rod 17 from sliding when the winged nut is loosened preparatory to adjustment of the slide rod. In other words, when the winged nut 25 is loosened the spring 26 acts in a manner to prevent slippage of the slide rod 17. In addition to forming a quick releasing means for a ready adjustment of the rod 17, the wedge locking member 23 also serves to permit a slippage of the rod 17 when excessive pressure is applied which pressure might result in distorting the tool.

Cooperating with the member 11 and slide rod 17 is a relatively movable or lower member 27, slidably mounted upon the supporting member 10. The member 27 at its outer end has a spring engaging bracket 28 which engages under the spring 20, as shown in Figure 6, for releasing the valve. The member 27 is secured to a guide member 29 embracing the supporting member 10 and is pivotally connected to one end of the link 30, the other end of which is pivotally con-

nected at 31 to one end of the hand operated lever 32 fulcrumed on a pin 33 carried by the support 10. Accordingly, when the lever is lowered from the position shown in Figure 1 to the position shown in Figure 6, the lower member 27 is raised and the spring 20 is compressed while the valve 19 is held down for permitting the removal of the valve key 21 and the release of the valve 19. When the lever 32 is moved upwardly the spring 20 is permitted to expand. It will be understood, of course, that after the valve key 21 is removed the valve 19 may be removed. Movable with the lever 32 is a ratchet wheel 35 with which a pivotally mounted two toothed pawl 36 cooperates. The pawl is connected by a spring 37 to a hand lever 38 pivotally mounted upon the support 10, the spring 37 being anchored at 45 intermediate its ends. As shown in Figure 1, the hand lever 38 has been moved into one extreme position wherein its lip 39 engages the support 10 for yieldably holding the pawl 36 in operative position with respect to the ratchet wheel 35. As shown in Figure 4 the hand lever 38 has been moved to its other extreme position wherein its upper portion engages the support 10 for yieldably holding the spring pressed pawl 36 in a neutral position. By means of this arrangement a mechanic using the tool may have only one hand applied to the tool and have his other hand free to guide the lower arm or fork 28 of the member 27 as the spring 20 is being expanded after collar key 21 has been set in place on the valve stem. It will be noted that one end of the slide rod 17 is provided with a semi-spherical or curved head 40 which is used in placing the valve spring prior to the insertion of the valve as shown particularly in Figure 7. In said figure it will be noted that the slide rod 17 has been reversed from its position shown in Figures 1 and 6 and that the rounded end 40 engages the valve guide 41. It will be appreciated that during the placement of the spring 20 before the valve is set in position, it is necessary that the valve spring lifter be pivoted about the curved head 40. Were this head not curved, the valve guide 41 will be burred or otherwise damaged if a sharp edge were used. However, by means of the curved head 40, it is a simple matter to pivot the valve spring lifter to place the valve spring 20 in position as shown in Figure 7. The member 27 may then be lowered to permit an expansion of the spring. The valve rod may then be inserted, then the sliding rod 17 may be reversed in position as shown in Figure 6 and the spring 20 again compressed to permit the insertion of the key 21, whereupon the member 27 again may be lowered for permitting the spring to expand and for locking the valve in position. The wedge locking

member 23 is prevented from falling out of the enlarged head 16 at all times because it is slightly tapered downwardly from its unthreaded to its threaded end.

By means of this valve spring lifter the objects of this invention are accomplished.

It is my intention to cover all modifications falling within the spirit and scope of the following claims.

I claim:

1. A valve spring lifter comprising supported relatively movable members, one of said members being engageable under the spring, a rod slidably mounted in said other member having one end thereof engageable with the valve for holding the latter down when the spring is being compressed, means for moving said members relatively to each other for compressing the spring for releasing the valve, and a slotted bolt extending through one of said members for receiving and releasably and frictionally locking said rod whereby a quick slideable adjustment of said rod may be made for operation on valves varying in length and to prevent distortion of said members due to excessive strain which otherwise would be transmitted through said slidably mounted rod.

2. A valve spring lifter comprising supported relatively movable members, one of said members being engageable under the spring, and a rod slidably mounted in said other member having one end thereof engageable with the valve for holding the latter down when the spring is being compressed, the other end of said rod being rounded for engagement with the valve guide for replacing the spring in the motor when the valve is removed, said rounded end acting as a pivot for the valve lifter mechanism for swinging the spring into position.

3. A valve spring lifter comprising supported relatively movable members, one of said members being engageable under the spring, a rod slidably mounted in said other member having one end thereof engageable with the valve for holding the latter down when the spring is being compressed, the other end of said rod being rounded for engagement with the valve guide for replacing the spring in the motor when the valve is removed, said rounded end acting as a pivot for the valve lifter mechanism for swinging the spring into position, and means for releasably locking said rod whereby a quick slideable adjustment of said rod may be made.

4. A valve spring lifter comprising supported relatively movable members, one of said members being engageable under the spring, a rod adjustably mounted in said other member having one end thereof engageable with the valve for holding the latter down when the spring is being compressed, the other end of said rod being

rounded to pivotally engage the valve guide to prevent injury to the latter as the valve spring is swung back into position when the valve is removed.

5. A valve spring lifter comprising supported relatively movable members, one of said members being engageable under the spring, and a rod mounted in said other member having one end thereof curved for

10 pivotal engagement with the valve guide to prevent injury to the latter as the spring is swung into place before the valve is inserted.

6. A valve spring lifter comprising supported relatively movable members, one of said members being engageable under the spring, a rod slidably mounted in said other member having one end thereof engageable with the valve for holding the latter down 20 when the spring is being compressed, means for moving said members relatively to each other for compressing the spring for releasing the valve, means for releasably locking said rod whereby a quick slidable adjustment of said rod may be made for operation on valves varying in length, and means normally to prevent slippage of said slide rod when the latter is released.

7. A valve spring lifter comprising supported relatively movable members, one of said members being engageable under the spring, a rod slidably mounted in said other member having one end thereof engageable with the valve for holding the latter down 35 when the spring is being compressed, means for moving said members relatively to each

other for compressing the spring for releasing the valve, a slotted bolt extending through one of said members for receiving and releasably locking said rod whereby a 40 quick slidable adjustment of said rod may be made for operation on valves varying in length, and a spring associated with said bolt normally to prevent slippage thereof when said bolt is loosened.

8. A valve spring lifter comprising supported relatively movable members, one of said members being engageable under the spring, a rod slidably mounted in said other member having one end thereof engageable with the valve for holding the latter down when the spring is being compressed, means for moving said members relatively to each other for compressing the spring for releasing the valve, and means normally locking said rod in adjusted position but which will permit a slippage thereof under excessive pressure to prevent distortion of the tool.

9. A valve spring lifter comprising supported relatively movable members, one of said members being engageable under the spring, the other member being operatively associated with the valve for holding the latter down when the spring is being compressed, said latter member being reversible 60 in position to vary the normal vertical distance between said members to adapt the lifter for wider use.

Signed at Chicago, Illinois, this 2nd day of September, 1926.

OTTO BLOMBERG.
